UNITED STATES PATENT OFFICE.

FRANK S. HICKEY, OF BOSTON, MASSACHUSETTS.

DESIGN FOR A PRAYER-BOX.

47,516.

Specification for Design.

Patented June 29, 1915.

Application filed May 3, 1915. Serial No. 25,614. Term of patent 3½ years.

To all whom it may concern:

Be it known that I, FRANK S. HICKEY, a citizen of the United States, residing at Boston, in the county of Suffolk and State of Massachusetts, have invented a new, original, and ornamental Design for Prayer-Boxes, of which the following is a specification, reference being had to the accompanying drawing, forming part thereof.

The figure is a perspective view of a "prayer box", showing my new design.

I claim:

The ornamental design for "prayer box" as shown.

FRANK S. HICKEY.

Witnesses:

DOROTHY A. GÖERES,
FRED. K. DAGGETT.
